CLAIM

I claim the ornamental design for a measuring tool for medical use, as shown.

DESCRIPTION

FIG. 1 is a top plan view of a measuring tool for medical use showing my new design;

FIG. 2 is a front view thereof;

FIG. 3 is a bottom plan view thereof;

FIG. 4 is a rear view thereof;

FIG. 5 is a left side view thereof;

FIG. 6 is a right side view thereof;

FIG. 7 is a perspective view thereof;

FIG. 8 is a perspective view of the measuring tool when placed on its side; and,

FIG. 9 is a front view of the measuring tool as seen by a user during use thereof.
